ELECTRICALLY ACTUATED PULSATATOR
PUMP

Cécile Ramigé, Suresnes, France

Application May 29, 1935, Serial No. 24,143
In France June 5, 1934

4 Claims. (Cl. 103—53)

This invention relates to a novel pump system adapted to serve for the raising or displacement of any kind of liquid.

This system which comprises essentially, in combination, a vibrating plunger member and an electromagnet actuated by a suitable alternating current, includes a chamber, the capacity of which may be subjected to variations due to the displacement or vibrations of the vibrating plunger member which forms one of the sides of the said chamber, the chamber having suitable liquid inlet and outlet means.

On the passage of the alternating current in the electromagnet, the rapid variations in the direction of the magnetic flux produce a vibratory movement in the above-mentioned plunger member. This movement produces in the chamber a rapid succession of compressions and expansions, that is to say, of deliveries and suctions of the liquid. The latter is thus displaced, through the chamber, from the source of the liquid and is delivered through the outlet means.

The accompanying drawing shows different constructional forms of pumps embodying the novel features of the invention.

Figs. 1 and 2 are a vertical section and a perspective view, respectively, of a practical form of construction comprising a jet.

Fig. 3 shows a modification in which the pump causes the liquid to circulate.

Fig. 4 shows another modification.

Fig. 5 is a section taken on the line *x—x* of Fig. 4.

Fig. 6 is a further modification.

Fig. 7 shows a device serving to prevent any back pressure in the suction pipe.

According to Fig. 1, the apparatus comprises essentially a U-shaped electromagnet 1 embedded in a suitable insulating material 2, for example resin or a hardened fatty body contained in a box 3 on which there is arranged, in a detachable and eventually adjustable manner, a cover 4 apertured at 5.

Between the cover 4 and the insulating body 2, are mounted two resilient discs 6, 7, for example of solid, hollow or sponge rubber.

Between these discs is gripped the rim 8 of a socket 9 passing through the orifice 5, the socket 9 being internally threaded to accommodate by screwing a tube 10 with a flanged base 11 and to the upper extremity of which is secured a jet 12.

Below the tube 10 there opens, by one extremity 13, a pipe 14 which may or may not comprise a valve and the other extremity 15 of which projects more or less outside the box or casing.

The wires 16 supplying the current to the electromagnet pass through a plug 17.

The apparatus thus comprises a rigid whole formed by the parts 9, 10, 12 and which is resiliently held between the discs 6 and 7.

The variations of the magnetic flux of the electromagnet cause the unit 9, 10, 12 to vibrate between the springs formed by the discs 6, 7. These vibrations resolve themselves into alternating movements of the flanges 11 and 8 towards 10 and away from the outlet 13 of the tube 14, producing, as a piston would do, alternate suctions and deliveries.

If the apparatus is placed in a liquid so that the whole box and its cover are below the surface of 15 the liquid, the tube 14 and the chamber 18 are filled with liquid and the rapid movements of the vibratory unit 9, 10, 12 cause the ascent of the liquid into the tube 10, which liquid then escapes through the jet 12 up to a height which can be 20 regulated by screwing the tube 10 more or less into the socket 9.

According to the modification shown in Fig. 3, the pipe 14^a is extended by a tube 14^b which, whether it terminates in a jet or not, can deliver 25 at a certain distance from the apparatus. The suction pipe 14^a may be provided with a valve if it is intended that the apparatus should cause the liquid to rise in a column. The pipes 14^a, 14^b communicate with the chamber 18 by a common 30 orifice 13^a and an adjustable solid member or plug 10^a is screwed in the socket 9.

In this arrangement, the socket 9 and the part or plug 10^a could be replaced by a diaphragm.

It would be possible to employ the device as a 35 double acting pump by utilizing, on each side of the diaphragm provided as above or at each extremity of the vibrator, a pipe or tube similar to that at 14^a—14^b with an orifice 13^a communicating with a chamber similar to the one 18 of 40 Fig. 3.

In the construction shown in Figs. 4 and 5, the liquid reaches the chamber 18 by a channel 19 passing between the ends of the branches of the electromagnet 1. This channel decreases in depth 45 but increases in width from the centre up to its ends, so that its area of cross-section remains constant.

This channel communicates with the outside by one or more orifices 20 in the box 3. 50

This arrangement is preferred when the apparatus is to be immersed in the liquid, only the jet 12 emerging therefrom.

But any suitable pipe system, shown dotted at 21 in Fig. 6, could be utilized to bring the liquid 55

to the apparatus from a source more or less distant from the point where the apparatus is located.

Thus, in order to avoid any back pressure in the pipes 14^a or 21 through which the liquid is drawn, the pipes could be made to comprise, before the suction valve 1^a (Fig. 7) a sleeve 23 of resilient material, for example, of rubber. The same effect could, however, be obtained by using a rubber tube 14^a or 21 which would expand at the moment of the closing of the valve 1^a. Any other similar means could be employed.

If the apparatus is not intended to be immersed, the insulation and the mounting of the electro-magnet 1 may be ensured, not by the material 2, but by a moulded or stamped part in which is formed the channel 19.

By screwing the cover 4 more or less tightly, the rings 6 and 7 are compressed to a greater or lesser degree and there is thus imparted to the apparatus the degree of regulation desired.

With the object of fixing the tube 10 in the socket 9 after each adjustment there may be used a rubber ring 23 which is compressed by means of a nut 24.

The jet 12 may comprise a nipple 25 and be held in the desired position by means of a nut 26.

If the apparatus shown in Fig. 6 is made to act as a water circulating pump, the jet 12 and the nut 13 are replaced by a plug screwed on the tube 10, as already provided in Fig. 3, a pipe 22 being placed opposite the one at 21.

The electromagnet may be of any suitable shape, for example, of the screened or armored type having a single central bobbin. In the central polar mass of this electromagnet is made a recess to take the liquid pipe, this recess corresponding to the zones 13, 18 or 19.

In all the devices above described, the box or casing 3 could be of any suitable shape adapted to the useful or decorative end in view.

The field of application of these apparatus may be very wide. By way of example, their use may be cited as water pumps, ornamental or like water jets or for the circulation of refrigerating water,

as oil pumps or petrol or water pumps for use with automobiles, aircraft, ships or the like.

The use of apparatus of this kind can also be pointed out as air humidifiers, for example in apartments provided with central heating where each apparatus would be located in a reservoir of water carried for example by a radiator. The jet of water produced by the apparatus would ensure the humidification of the air.

It will be understood that by adjusting the member 10 or 10^a in its socket 9 the volumetric capacity of the pump chamber may be varied to vary the output of the pump. It will also be understood that the upper resilient element 6 and the cover 4 are not essential, as the pump will operate without them.

What I claim is:

1. A pump comprising a vibrating member, electro-magnetic means, a resilient element between said vibrating member and said electro-magnetic means serving to support said vibrating member in operative relationship to said electro-magnetic means so that when an alternating current is passed through said electro-magnetic means said member is vibrated, said resilient element being hollow and being closed at its ends by said vibrating member and said electro-magnetic member whereby there is provided a pump chamber, and fluid inlet and outlet means leading to and from said pump chamber.

2. A pump as set forth in claim 1 including means carried by and adjustable relative to the vibrating member into and from the pump chamber to vary the volumetric capacity thereof.

3. A pump as set forth in claim 1 including a check valve in the fluid inlet means, and yieldable seat means for said check valve to absorb back pressure.

4. A pump as set forth in claim 1 in which the electro-magnetic means includes a body of material in which the electro-magnet is imbedded and against which the hollow resilient element seats, and in which said body of material is provided with a channel forming the inlet and outlet means to and from the pump chamber.
